SYSTEM FOR INDICATING THE PRESENCE
AND LOCATION OF FIRE

Harry Campbell Grant, Jr., New York, N. Y., assignor to Walter Kidde & Company, Inc., New York, N. Y., a corporation of New York

Application November 21, 1929, Serial No. 408,740

12 Claims. (Cl. 177—355)

The present invention relates to systems for detecting the presence of fire and embodies, more specifically, an improved detecting system which indicates the exact location of such fire.

5 Most of the existing fire detecting systems merely indicate the presence of a fire within the area protected by the fire detecting system. In thermostatic fire detecting systems employing a considerable number of open circuited thermostats which are bridged across two wires of an external circuit, and in which the functioning of a thermostat causes a signal to be displayed at a central station which indicates the number of the circuit to which the thermostat belongs, 10 there has been effected a grouping of the individual thermostats to indicate, by a suitable signal, the general location of the fire. In such improved construction, however, it has been necessary for the fire watch attendant to inspect 15 the various spaces protected by the indicated circuit in order to determine the particular space in which fire has occurred.

The enormous expense of providing a system in which the exact location of a fire is ascertained by employing separate circuits for each thermostat and space to be protected, such circuits including the central station, will be readily apparent. As an improvement over the available fire detecting systems, the present invention provides a means for indicating the exact thermostat, and space protected thereby, at the central station without requiring a number of wires running to the central station equal to the number of spaces or thermostats employed. With 25 this minimum of wiring, a maximum amount of protection is afforded and a detailed signal, or indication, is quickly given to locate the fire definitely.

An object of the invention, accordingly, is to 40 provide a fire detecting system which indicates the exact location of a fire within the space protected by the system.

A further object of the invention is to provide a system of the above character in which a plurality of heat responsive mechanisms are employed, the system being of such character that the specific heat responsive device actuated by a fire may be quickly ascertained.

As the invention is described more fully, and 50 the character thereof more readily understood, further objects thereof will be apparent, the same being too numerous to attempt a detailed enumeration thereof herein and reference will now be had to the accompanying drawings wherein:

55 Figure 1 is a wiring diagram showing sche-

matically a fire detecting system constructed in accordance with the present invention.

Figure 2 is a wiring diagram showing a modified fire detecting system constructed in accordance with the present invention. 5

Figures 3 and 4 are diagrammatic views showing the system of Figure 1 enlarged.

Figure 5 is a diagrammatic view showing the right hand portion of the system of Figure 1 enlarged to complete, with Figures 3 and 4, the enlarged showing of the system. 10

Referring to the above drawings, a battery is indicated at BAT, having its positive terminal connected to a positive bus wire 1 which includes a battery supervising relay 2, a switch S_c having switch points 3 and 4, connections 5 and 6, switch S_m having switch points 7 and 8, and positive bus wire 9. A plurality of external circuits, in which thermostats or other suitable heat operated devices are connected, is used in connection with the system shown and described herein, but for the purposes of description and in the interest of clarity, only two such circuits have been shown. These circuits have been marked as A and B and one side of each of these circuits is connected to the positive bus wire. Since the circuits A and B are identical and are connected to similar relays and associated elements, only the connection for circuit B will be described herein, it being understood that the corresponding elements of circuit A, as well as other circuits, not specifically shown, function in the same manner as the elements of circuit B. The other side of each external circuit is connected to the negative terminal of the battery and the elements for so connecting these circuits include, in the case of circuit B, a wire 16, a contact 17, a trouble alarm relay T₁, a fire alarm relay M₁, wire 18, wire 19, and negative bus wire 20, such negative bus wire being connected to the negative terminal of the battery. 30 35

It will thus be seen that a supervisory current flows through the external circuit, the trouble alarm relay T₁ and the fire alarm relay M₁. If a break should occur in the wire so that current 45 through the trouble alarm relay T₁ is interrupted, this relay will be deenergized and will close contacts 21 and 22, causing a trouble alarm lamp L₁ to be lighted. Current flows through the trouble alarm lamp L₁ from the positive bus wire 9 50 through the lamp, contact 21, to connection 23, contact 24, and connection 25 to the negative bus wire 20. This light indicates trouble in the external circuit B. At the same time, the general trouble alarm bell T. B. is sounded since it is con- 55

nected to the positive bus wire through wire 10, point 26, point 27, point 28, point 29, through the bell T. B. point 30, wire 32, points 33, 35, and 37, contact 22, contacts 38 and 39 of switch S₁, point 5 23 through contact 24 and point 25, to negative wire 20. In order to clear the general trouble alarm bell so that it may be free to indicate trouble in other circuits, the switch S₁ is thrown to the left to make contact at point 40, thus opening 10 the circuit through the general trouble alarm bell and clearing the bell for the indication of trouble in the other circuits. The trouble alarm lamp L₁ remains lighted until the trouble has been repaired, whereupon the trouble alarm 15 relay T₁ picks up its armature thus opening the contacts 21 and 22. The trouble alarm lamp L₁ remains lighted, however, by reason of its connection from the positive wire 9 to the successive points 40, 39, 23, 24, and 25. In order to clear 20 the trouble alarm lamp L₁, the switch S₁ is thrown to its normal position at the right, as viewed in the figure, to make contact at point 38.

The battery supervising relay 2 is in series 25 with the circuit supplying current to the external circuits, and if the current from the battery should fail, the battery supervising relay 2 will be deenergized and close contacts 41 and 42, thus causing the battery supervising trouble alarm lamp L₂ to be lighted and the general trouble 30 alarm bell T. B. to be sounded. A switch S₇ is provided to clear the general trouble alarm bell in the same manner as that described in connection with the trouble alarm relay T₁.

Two fire alarm bells are provided, one supervised and one unsupervised. The supervised fire alarm bell is indicated at S. A., while the unsupervised bell is indicated at U. A. The supervised bell is in series with a relay 43 which is of such resistance as to prevent the ringing of the 35 supervised fire alarm bell, at the same time permitting a supervisory current to flow. The supervisory connection is from the positive wire 9 to the successive points, 26, 27, and 28, through the supervised fire alarm bell to the point 44, 40 through the winding of the relay 43 and connection 45 to the point 46 on the negative bus wire 20. If the supervised alarm bell should become inoperative, the supervising current will fail and the relay 43 will become deenergized, 45 thus permitting the closing of its contacts at 47 and 48, thus lighting the supervised fire alarm bell trouble alarm lamp L₃ and sounding the general trouble alarm bell. The switch S₆ is provided for clearing the general trouble alarm 50 bell in the same manner as that described in connection with the trouble alarm relay T₁.

A fuse 221 will be found in one lead to the supervised fire alarm bell. The reason for installing this fuse is that the resistance of the 55 winding of the supervised fire alarm bell is ordinarily only a fraction of one percent of the resistance of the winding of the fire alarm bell supervising relay 43. If a short circuit of the supervised fire alarm bell leads should occur, no trouble signal would be given because the short circuit of the winding of the supervised fire alarm bell would allow a slightly greater supervising current to flow through the supervising relay, this increase in current not being, however, 60 great enough to blow the fuse 221. If a fire signal should be given, at which time the high resistance of the supervised fire alarm bell supervising relay is cut out of the circuit, the short circuit of the fire alarm bell connecting wires 65 70 would constitute a direct short circuit across the

source of current and, therefore, the fuse 221 is placed in one lead to the supervised fire alarm bell to relieve, immediately, this short circuit condition which otherwise would seriously affect the operation of the other circuits of the system. The blowing out of this fuse places the system in a condition to render a delayed trouble signal in a manner to be described herein-after. 5

A resistance 49 is connected in the external 10 circuit B at the extreme end thereof and this resistance is of such value as to limit the current which flows through the trouble alarm relay T₁ and the fire alarm relay M₁ to a value below that necessary to cause the fire alarm relay M₁ to pick 15 up. If, however, by reason of a fire in one of the spaces protected on the circuit B, a thermostat should function and thus short circuit the resistance 49, sufficient current will flow through the circuit already described and cause the fire 20 alarm relay M₁ to pick up its armature and close contacts at points 50, 51, 52, and 53, at the same time breaking the contacts at the points 17 and 24. The fire alarm relay M₁ is so constructed 25 that the contact 51 will make before the contact 17 breaks. The purpose of contact 17 is to connect the resistance of the external circuit across one portion of a Wheatstone bridge as described 30 hereinafter.

The opening of the contact 17 would result in 35 the deenergization of the fire alarm relay M₁ were it not for the closing of contact 51 before the opening of contact 17. By reason of the closing of the contact 51, a connection is made through the winding of the fire alarm relay M₁ 35 from the positive bus wire 9 to the successive points 54, 55, 56, 57, wire 58, connection 59, wire 60, connection 61 through contact 51, the winding of fire alarm relay M₁, wires 18 and 19, to the negative bus wire 20. The fire alarm relay M₁, 40 therefore, remains energized until the circuit through its winding is manually opened in the manner described hereinafter.

Upon the closing of contact 52, a relay 62 is 45 energized by reason of its connection to the positive bus wide 9 through wire 10, and connection 26, cabinet door switch C. D. S. and to the negative line through point 63, wire 64, through the contact 52, to the point 25. Upon energization 50 of the relay 62, contacts 66, 67 and 68 are closed, 55 while contact 69 is broken. The closing of the contact 68 short circuits the supervised fire alarm bell supervising relay 43 and permits the supervised fire alarm bell to sound by reason of its connection from the positive wire to the successive points 26, 27, and 28 through a wire 10 60 to the point 44, through a wire 71, through contact 68, to the point 45, and thence to the point 46 on the negative line. By reason of the short circuiting of the supervised fire alarm bell supervising relay 43, the relay 43 is deenergized and the contacts 47 and 48 are closed. This would cause trouble alarm lamp L₃ to light and the general trouble alarm bell to sound if it were not 65 for the fact that the contact 69 of the relay 62 opens the connection from the trouble alarm lamp and from the general trouble alarm bell to the negative line. It will be seen that the trouble alarm lamp circuit is from the positive wire 9 to the successive points 26, 27, 72 through the trouble alarm lamp and contact 47 to a point 73 70 (where the line from the general trouble alarm bell joins a common return 74), through such common return to the contact 69 and the negative line wire.

The unsupervised fire alarm bell U. A. is caused to ring at the same time as the supervised fire alarm bell, the circuit for accomplishing such ringing being closed through the contact 67. Current flows from the positive wire 9 to the successive points 26, 27, 28, and 29, through the unsupervised fire alarm bell U. A. and through contact 67 to the negative line. Closing of the contact 66 produces an operation which will be described more fully hereinafter.

External circuit fire alarm lamps A', B', C', D', E', F', G', H', I', J', K', etc. corresponding to the external circuits A, B, etc. are connected in series with a supervising relay 75. The supervising current flows through a circuit from positive wire 9 through a wire 111 to a connection 76, through a wire 126 to a connection 77, through contact point 78 to connections 79, 80, wire 81, connections 82, and 83, contact point 84, connections 85 and 86, wire 87, connection 88, contact 89, connection 90 and wire 91, connections 92 and 93, contact 94, connections 95 and 96, wire 97, connection 98, contact 99, connection 100, wire 101, connections 102 and 103, wire 104, relay 75, connection 105 and wire 106 to negative wire 20. Since the external circuit fire alarm lamps are in series, if any of the lamps become defective, the supervising current will cease and the relay 75 will be deenergized, closing its contacts 109 and 110. Closing contact 109 establishes a connection from the positive wire 9 through wire 111 to point 76, through the trouble alarm lamp L₄ through the contact 109, point 112, through wire 113 and contact 114 to wire 115 and the negative wire 20. At the same time, connection is established from the positive wire 9 to the successive points 26, 27, 28, and 29 through the general trouble alarm bell to the point 30 through the wire 32 and point 33, wire 116 to contact 110 and point 117, through switch S₁₀ to point 112 and negative wire as described above, thus causing the sounding of the general trouble alarm bell. The switch S₁₀ is provided for clearing the general trouble alarm bell in the manner already described in connection with the trouble alarm relay T₁.

At the same time that a fire alarm relay, for example, M₁ is energized with consequent energization of the relay 62, a relay 118 is energized by reason of its connection from the positive wire through the wire 111 to the points 76 and 77, through the winding of the relay 118 to a point 119 and through a wire 120 to the point 63 which is connected to the negative line through wire 64, contact 52 and point 25. Upon energization of the relay 118, the contacts at 78, 84, 89, 94, 99 and 114 are broken, while contacts are closed at 121, 122, 123, 124, and 125. The external circuit fire alarm lamp B', corresponding to the external circuit B, is then lighted by reason of its connection from the positive wire 9 through the wire 111 to the point 76, through wire 126 to point 77, through contact 121 to point 80, through wire 81 to point 82, through contact 122 to point 127, through contact 123 to point 128, through contact 124 to point 129, through contact 125 to point 102, through wire 101 and fire alarm lamp B' to point 100, through wire 131 to contact 53, and to connection 25 on the negative line. The reason that the deenergization of the relay 75 does not result in lighting the trouble alarm lamp L₄ and ringing the general trouble alarm bell upon the breaking of the contacts at 78, 84, 89, 94, 99, and 114 is that the contact 114 is in the line

which connects the trouble alarm lamp L₄ and the general trouble alarm bell to the negative line. When the contact 114 is opened, the trouble alarm lamp L₄ and the general trouble alarm bell cannot function.

The foregoing description has dealt chiefly with the various means for indicating trouble and with the means for indicating the particular circuit from which a fire signal has been given. It will be seen that the foregoing construction will function equally well regardless of the number of external circuits and the corresponding fire alarm lamps which are connected therewith. The following description is concerned principally with the means for detecting the exact thermostatic circuit closer which has functioned in the particular external circuit.

A Wheatstone bridge connection is provided including resistance elements 133 and 134, the resistance of the external circuit which has been actuated, and a variable known resistance indicated generally at 137. Point 132 of this connection corresponds to the connection of the resistance elements to the negative side of a battery circuit, while point 136 is the connection to a galvanometer and the unknown resistance which is the resistance of the external circuit. Point 135 is the connection to the other side of the galvanometer and to one terminal of the variable known resistance 137. It will be seen that point 132 is connected through a resistance 138 to points 139, 140, wire 141, contact 249, contact 241 to the negative wire 20.

Point 135, on the other hand, is connected to the positive line through wire 144, resistance 145, movable contact 146, point 147, wire 148, resistance 149, and point 150 to a movable contact 151 and point 152 through wire 153 which is connected to the positive line through point 154 and wire 155 to point 54 and positive wire 9. One side of the external circuit B is connected to the positive line and the other side of the circuit B, upon energization of the fire alarm relay M₁, is connected to the point 136 through wire 16, contact 50, point 156, wire 157, point 158, wire 159 and point 136.

Upon the occurrence of fire in any space, the fire alarm relay, corresponding to the circuit by which such space is protected, is energized. A fire alarm lamp indicating the circuit is lighted and the fire alarm bells are sounded. The resistance of that portion of the external circuit lying between the positive line and the particular thermostat which has functioned, is brought into proper relation with the Wheatstone bridge arrangement for permitting the automatic balancing of the resistance of the external circuit and the consequent determination of the particular thermostat which has functioned. The variable resistance 137 consists of a rotary switch such as is now employed in automatic telephone work, resistances being connected between each of the adjacent points of the rotary switch.

With reference to the external circuit B, it will be seen that the path of the supervisory circuit from the positive wire 9 is through a compensating resistance 160, a resistance U₁, the terminal of a thermostat TT₁, a resistance U₂, through the terminal of a thermostat TT₂, etc. there being similar resistances before each thermostat. With reference to the variable resistance arrangement 137, the resistance 149 is of the same value as the resistance U₁; and the resistances R₂, R₃, R₄, etc. are of the same values as the corresponding resistances U₂, U₃, U₄, etc. all of the resistances

being of the same value. If, therefore, the contact 146 is moved from the first point of the rotary switch to any other point, there can be cut into the Wheatstone bridge arrangement, enough 5 resistance to balance the resistance from the external circuit which is thrown in as another leg of the Wheatstone bridge arrangement.

The automatic balancing of the resistance of the external circuit is accomplished through the 10 medium of the Wheatstone bridge arrangement in combination with a galvanometer relay, the relay being so connected to the circuit that its contact remains closed as long as the balancing resistance 137 is less than the resistance of the 15 external circuit. It will be seen that the variable resistance 137 has been shown with the movable contact 146 on the first point of the rotary switch. This is the normal position of rest at which time only the resistance 149 is in the balancing 20 resistance circuit so that the resistance is always less than the resistance thrown in from the external circuit (except for the first resistance, which will be discussed later on). If, therefore, any thermostat beyond the first one functions, a resistance greater than the balancing resistance will be thrown across the proper leg of the Wheatstone bridge, and the galvanometer relay contact 161 will be closed.

As soon therefore, as a fire alarm relay, such 30 as M₁ is energized, a relay 162 is energized by reason of its connection from the positive wire 9 through the connection 54, line 155, connection 154, wire 153, connection 163, wire 164, contact 165, wire 166, through relay 162, galvanometer 35 contact 161, wire 141, contact 240, contact 241 to the negative wire 20. When the relay 162 is energized, the contact 171 is closed. This results in energizing relays indicated as Mot. 1 and Mot. 2, by reason of their connection with the positive 40 wire 153 through the motor relay windings, the parallel relay contacts 243 and 244, respectively, wires 245' and 245'' and connection 245, wire 246, connection 247, contact 171, connection 105 and wire 106 to the negative line wire 20. 45 Upon the closing of the contact 171 of the relay 162, connection is established from the positive line to the negative line. The slow acting relay 237 is thus energized and contact 165 opened, thus deenergizing relay 162 so that contact 171 is opened and slow acting relay 237 deenergized. 50 This cycle of operation is repeated as long as the galvanometer contact 161 is closed. At the same time that the slow acting relay is deenergized by the opening of the contact 171 of the relay 162, the motor relays Mots. 1 and 2 are deenergized and simultaneously with the deenergization of the motor relays, the movable arm 146 moves one step from the first to the second point of the rotary switch. The same cycle is 55 repeated until the amount of the balancing resistance 137 which has been cut in, is equal to, or greater than, or even somewhat less than, the cut-in portion of the resistance of the external circuit. As soon as this condition is reached, the 60 current flow through the galvanometer winding either weakens sufficiently, ceases, or reverses, so that the galvanometer contact 161 is broken, as well as the circuit through the relay 162. The 65 rotary switch has therefore come to a position of rest and can be made to indicate the exact 70 thermostat which has functioned. This will be described in greater detail hereinafter. While in a theoretically perfect circuit the balancing resistance can be considered as exactly balancing the resistance of the external circuit, the resistance 75 of the external circuit might be somewhat

less than the proper balancing resistance due to slight negative errors in winding the resistance units U₁, U₂, etc., while it might be somewhat more than the proper balancing resistance due to more wiring being used in the external circuit than the theoretically correct amount. The galvanometer relay is therefore adjusted to operate over a range such that the correct balancing resistance will be cut in not only when the resistance of the external circuit equals the proper balancing resistance, but also when it is within predetermined negative and positive variations from the proper balancing resistance. 5

Under certain conditions it might happen, that due to an excessive length of wire in an external 15 circuit, the total resistance of the external circuit at the last thermostat, for example, consisting of the wire resistance of the circuit plus the total resistance of all of the unit resistances U₁, U₂, etc., will exceed the total balancing resistance sufficiently to make a balance impossible when the last thermostat functions, so that the rotary switches will continue to rotate in attempting to seek a balance. In order to make this continuous rotation impossible, it is desirable to maintain 20 an open circuit (with infinite resistance) between points of the rotary switch, as shown in the drawings between the points 49th and 50th, so that a complete over-balance will be obtained when the last thermostat functions, thus causing 25 the rotary switch to come to rest on the last point.

In the upper right hand corner of the figure there will be seen six rows of contacts. While 30 all of these contacts could be arranged on a single 35 rotary switch, it so happens that the rotary switches which are employed as standards for automatic telephone work contain the equivalent of three rows of contacts and it has therefore been necessary to illustrate connections to two 40 rotary switches, which are operated in unison by the parallel motor relays 1 and 2. While any number of thermostats can be connected to a single circuit, the rotary switches diagrammatically indicated show contacts sufficient for the 45 connection of fifty thermostats, this limitation being imposed by the commercially obtainable switches. Although it has been stated that a 50 resistance is connected between each adjacent contact point of the switch, the fact is that these resistances are connected only between the first nine contact points, and one before the first, making a total of nine resistances; the first, eleventh, twenty-first, thirty-first, and forty-first, being 55 connected in parallel, similar connections being made for the other points. These connections are all made between the points of the first row of contacts. With reference to the second row of points, a resistance R₁₀, equal to the value of the sum of ten of the unit resistances, is bridged 60 across the points 9 and 10, points 19 and 20, points 29 and 30, and points 39 and 40. It will therefore be seen that no matter what the resistance is which is thrown in from the external circuit, the proper balancing resistance can be obtained 65 through the movable contact 146, wires 148 or 130, and the movable contact 151.

The third and sixth rows of contacts are employed in connection with the resetting of the system and will be described in detail hereinafter. 70

The fourth and fifth rows of points are provided for lighting suitable lamps to indicate the exact thermostat which has functioned. On the assumption that the first thermostat has functioned, the lamp 0 of the tens column and the lamp 1 75

of the units column will be lighted in the following manner. The positive line wire 9 is connected to all of the lamps of each column and current flows through the proper lamp, in the hypothetical instance the lamp 9, of the tens column to point 174, through a movable contact 175, connection 176, wire 177, and wire 143 to the connection 119, wire 120 and connection 63 to wire 64, and contact 52 to connection 25 on the negative line. At the same time, current flows from the positive wire 9 through the units lamp 1, wire 179, movable contact 180, and through the connection 176 and path just traced. The connection of the points in the fifth row is such that a single set of lamps will serve for the unit indications, while the connection in the fourth row is such that one lamp is required for each of the tens of the series of thermostats and balancing resistances.

It will be understood that a Wheatstone bridge circuit will distinguish a definite resistance value most readily when the total resistance in the bridge circuit is low. The galvanometer relay must, therefore, be permanently adjusted to distinguish between the last and the next to the last thermostat (when the bridge circuit is highest) with the maximum available voltage across the bridge. If the bridge circuit resistance is now called upon to distinguish between the first and the second thermostat (where the bridge circuit is lowest) it will be found so sensitive as to be affected by any low extra resistance inadvertently introduced by the circuit connecting wires, with the result that the rotary switch may advance one step beyond the correct point. In order to reduce this sensitivity at the low resistance end, the voltage across the bridge circuit proper is materially reduced by the introduction of a resistance, such as 138, placed in the voltage lead to the bridge. Therefore, in normal rest position, this resistance is in the bridge circuit so that regardless of the particular thermostat which may function, the bridge circuit first begins operation with its most insensitive adjustment. If a thermostat toward the end of the circuit has functioned, the bridge circuit automatically increases its sensitivity as it approaches the resistance ranges where increased sensitivity is needed. A sensitivity changer is shown as a relay 182. Assuming, by way of example only, that the resistance 138 is to be cut out after a balancing resistance equivalent to the external circuit resistance up to and including the tenth thermostat has been cut in, the short circuiting of the resistance 138 is accomplished by a connection from the positive wire 9 to the point 181, through the sensitivity changer relay 182, contact 183, wire 184 and point 185 which is the negative side of the lamp 1 of the tens column, this lamp being the one that is lighted on the assumption already made that resistance 138 is to be cut out at this point. The relay 182 is therefore energized, thus breaking the contact 183 and establishing contacts at 186 and 187. The contact 186 maintains the circuit through the winding of the relay 182 closed from the positive point 181, through the wire 188, to the point 189, through the interconnected points 190 and movable contact 191, to the negative line 20. As can be readily seen, the closing of the contact 187 directly short circuits the resistance 138. This resistance remains short circuited until such time as the movable contact 191 is returned to the first point of the switch, which is not connected to the remaining points 75 so that the connection from the point 190 to the

movable contact 191 (now on the first point) is broken.

Relay 237 is a very slow acting relay to permit motors 1 and 2 to complete, with certainty, a cycle of operation before a new cycle is instituted. As before described, when galvanometer contact 161 is closed, connection is established from the positive line at 163, through contact 165, wire 166, relay 162 and galvanometer contact 161 to the negative line. Relay 162 is thus energized and contact 171 closed so that connection is established from the positive line at 228, through the winding of the relay 237, through contact 171 and to the negative line. The relay 237 is thus energized and contact 165 opened 15 thus deenergizing relay 162 so that contact 171 is opened and relay 237 deenergized. This cycle of operation is repeated as long as the galvanometer contact 161 is closed. Each time that contact 171 is closed, connection is established from 20 the positive line through the windings of the motor relays 1 and 2 through parallel contacts 243 and 244, connection 245, wire 246, to the point 247 and through contact 171 to the negative line, thus energizing Mots. 1 and 2. As already explained relay 237 is very slow acting and thus serves to insure complete operation of both motor relays 1 and 2 before relay 237 opens the contact at 165. Such opening results in the deenergization of relay 162 and the opening of 30 contact 171, which results in the deenergization of the motor relays 1 and 2 and of the slow acting relay 237.

In order to reset the system, the push button switch 194 is operated to make contact with the point 192. Breaking the contact at 55 causes the deenergization of the fire alarm relay M₁ with the consequent return to normal conditions of the apparatus controlled thereby. Connection is thus established from the positive line at 54 to the point 192, through wire 250 to connection 251, through the windings of relay 252 and 253, to points 254 and 255, to the interconnected points of the two rotary switches through wires 254' and 255'. From these respective interconnected 45 points, the circuit is completed to the negative line through points 235 and 236. The relays 252 and 253 are therefore energized, causing the respective contacts at 241 and 243 for the relay 252, and 240 and 244 for the relay 253 to be broken 50 and contacts 266, and 257, to be closed for the relay 253, while the corresponding contacts are closed for the relay 252. With the closing of the contacts 256 and 257, connection is established from the positive line 153, through points 152 55 and 232, through contact 257 and line 250, to the point 251, through the windings of the relays 252 and 253 to the points 254 and 255 to the interconnected points of the rotary switches and thus to the negative line. Even though the push button switch 194 is returned to its normal position in contact with point 55, the relays 252 and 253 remain energized until such time as movable contacts 191 and 198 rest upon the first points of the respective rotary switches. Through the 65 closing of the contact 266 of the relay 253, connection is established from the positive line through the motor relay 2, through the contact 266, contact 169, to the interconnected points of the rotary switch and thus to the negative line. 70 Corresponding action occurs for relay 252 and results in energization of the motor relay 1. At the same time, contact 169 is opened and the motor relay 2 is deenergized, causing the advance of the rotary switch one step. After such ad. 75

vance, the contact 169 is again closed and the motor relay is again energized. Such operation continues until the movable contact 191 rests upon the first point of the rotary switch. If, for any reason, motor 2 should get out of step with motor 1, motor 2 will not continue to operate its rotary switch but will come to rest because it is no longer energized after the movable contact 191 rests upon the first point of the rotary switch. 5 Motor 1 is therefore free to return the other rotary switch to its initial position without being affected by the action of motor 2.

The switch 208 is a push button switch similar to the push button switch 194 and interconnected with the switch 194 in a series parallel arrangement, and is controlled by the opening of the door of the cabinet in which all of the apparatus is arranged. Upon the occurrence of fire, the fire alarm bells sound and the system automatically balances itself. The fire watch attendant then runs to the central station and opens the door of the cabinet, thus causing the switch 208 to momentarily close the circuit from the point 56 to the point 193, causing a resetting action to occur in the same manner as caused by the push button switch 194. As soon, however, as the movable contacts reach the first switch points, the fire indication is repeated and the fire watch attendant can determine from the lamps which 10 are lighted, the space which is afire. He can then push down the manual reset push button 194 and reset the system, and when the movable contacts again reach the first switch points the fire indication will be again given as a check 15 upon the initial reading. This resetting operation can be made as many times as the fire watch attendant desires in order to be sure that the apparatus has functioned properly and that the proper space has been indicated.

40 After the fire has been extinguished and the thermostat has been renewed, the door of the cabinet can be closed and the system will again be in its normal condition. If it should be forgotten to reset the system by means of the manual push button 194, the closing of the door will accomplish the resetting action through the closing of the push button switch 208.

In the wiring up of the external circuits, the distance between the various spaces protected, 50 and consequently the amount of wiring between the adjacent thermostats, is most likely to vary and cause a variation in the total resistance of the circuit. It may be necessary, therefore, to install at certain predetermined intervals, compensating resistances, as for example, 160 and 209. These resistances are normally adjusted to an intermediate value and can be adjusted one way or the other to make the resistance at various 55 points along the line the correct value, the value of the compensating resistance being such that it can balance out any variations which are likely to occur between itself and the preceding compensating resistance. A compensating resistance (for circuit B the compensating resistance is 160) is also required before the first thermostat due to the fact that there may be considerable variance in the resistance of the wires run from various points to the central fire detecting station. For every 60 compensating resistance installed in an external circuit there must be a corresponding compensating resistance inserted between the proper contacts of the rotary switch. Thus compensating resistance 145 is inserted before the movable contact 146 to correspond to the compensating resistance 160 in the external circuit B, and a

compensating resistance 210 is inserted between the fourteenth and fifteenth contacts in the second row of contacts to correspond to the compensating resistance 209 between the fourteenth and fifteenth thermostats in the external circuit B. Furthermore, it should be noted that whenever a compensating resistance is placed in any external circuit, a compensating resistance must be inserted in the corresponding position in every other external circuit. 5

10 A door switch C.D.S. is provided in the circuit of the fire alarm bell ringing relay 62, so that upon the opening of the cabinet door the fire alarm bells will stop sounding. If, however, the cabinet door is closed before the short circuited thermostat has been restored with a new, open circuited thermostat, the bell will again ring and indicate the failure to restore the thermostat. Attempting to reset the apparatus without restoring the thermostat will merely result in the repetition of the 15 fire signal.

If on the other hand, the cabinet door is left open, as it should be until the thermostat has been restored and if the thermostat is removed from the line (the thermostats are not bridged across two continuous wires, but the external circuit wires are run in sections between the thermostats, and the thermostats are designed so that when removed, they break both sides of the 20 external circuit and thus initiate a trouble signal), the trouble signal will not be given because the fire alarm relay has remained energized and the trouble circuit has been disconnected, but the wire break left by the removal of the thermostat constitutes an infinite resistance thrown across 25 one leg of the Wheatstone bridge, and the arm of the rotary switch advances to the last point of the balancing arrangement when an infinite resistance is then thrown in to balance the infinite 30 resistance of the open external circuit. When the thermostat has been restored, the arm of the rotary switch still rests on the last point because the current limiting resistance in the external circuit is great enough to require the infinite resistance to balance it, no other balancing resistance being available. All during this time the 35 external circuit fire alarm lamp has remained lighted. If now the cabinet door is closed, the reset button operated by the closing action of the door will cause the fire alarm relay to be deenergized and the system to be restored to its normal 40 condition, the rotary switch arm advancing to the first point.

If on the other hand, someone should close the cabinet door between the time the short circuited thermostat was removed and a new thermostat installed, the fire alarm signals will be cleared immediately, and the trouble signal will be given. If, still further, a thermostat should be removed 45 from an external circuit, the condition of the system being initially normal (for example, no fire signal has been previously given), the trouble signal will be immediately given, indicating a wire break. 50

55 Reference has been made hereinbefore to the use of a fuse 221 in the supervising circuit of the supervised fire alarm bell for the purpose of preventing the failure of the system due to a short circuit of the supervised fire alarm bell. As previously described, the fuse 221 is designed to blow 60 out at the time that a fire signal is given. As soon as the cabinet door is opened to stop the sounding of the fire alarm bells, the bell ringing relay 62 is deenergized and the circuit through the trouble signal is closed so that the delayed trouble 65 signal is given. 70

signal hereinbefore referred to is thus given, together with the fire signal.

It is contemplated that the thermostats TT₁, TT₂, etc., and the corresponding unit resistances U₁, U₂, etc., be built as complete working units. Under these circumstances it is conceivable that a fire might be so severe as to destroy the unit resistance of the functioning thermostat so that the fire signal would not be given except 10 momentarily, after which an open circuit would exist and the rotary switch arms would come to rest on the last switch point (for the reason previously given), instead of indicating the space afire. In order to overcome this difficulty, the 15 thermostats and unit resistances may be built as units as before, but the resistance associated with the first thermostat is to be connected into the lead to the second thermostat instead of into the lead from the central station to the first 20 thermostat. The unit resistance associated with the first thermostat will control the fire signal given by the second thermostat, the second and first unit resistances will control the fire signal given by the third thermostat, etc., so that the 25 destruction of a unit resistance associated with a particular thermostat will not effect the fire signal to be given by that thermostat.

In the explanation given at the beginning of this description, the battery was pointed out as 30 the source of energy for furnishing the supervising current. This reference was made for simplification of the description. In reality the battery is under trickle charge, the actual current normally supplying the supervising current to the 35 positive line 9 being obtained directly from the power supply terminals indicated to the right of the battery terminal. The normal path of the supervising current is from the positive terminal 212 of the power supply to the point 213 40 through the contact 214 through the successive points 215, 216, and 217, through the wire 218, through the contact 219, through the successive points 5, 6, 7, and 8 and then through the external circuits back to the negative line in the 45 manner already described. It will be noted that the contact 219 short circuits the resistance 220.

The path of the battery charging current is from the positive terminal 212 of the power supply to and through the successive points 213, 214, 50 215, 216, and 217, through the contact 219, to and through the successive points 5, 4, and 3, through the winding of the relay 2, to the positive terminal 1 of the battery, and then to the negative line.

55 It so happens that when the fire alarm bells are sounding, a much greater current is required from the power supply, and the tendency would be for the voltage across the system to decrease below the battery voltage. In order to prevent such decrease, a portion of the resistance in the power supply circuit is cut out. This resistance is shown at 223 and is short circuited by the closing of the contact 66 of the bell ringing relay 62.

On the other hand, if the battery should for 60 any reason go off the line, a smaller current would be drawn from the power supply, and the tendency would be for the voltage across the system 70 to increase. In order to prevent such increase, additional resistance must be added to the power supply line. This resistance is shown at 220, and is added by the removal of the short circuit at the contact 219 of the battery supervising relay 2, 75 which is deenergized upon the failure of the bat-

tery, with the result that the contact 219 is opened.

The power supply is supervised by the relay 224 which is deenergized upon the failure of the power supply, causing the contacts 225 and 226 5 to be closed, at the same time opening contact at 214 in order to prevent the discharge of the battery back through the circuits which may also be connected across the power supply. The closing of the contact 225 results in the lighting of 10 the trouble alarm lamp L₅ and the closing of the contact 226 results in the sounding of the general trouble alarm bell. The switch S₈ is provided to clear the general trouble alarm bell, in 15 the manner already described in connection with the trouble relay T₁.

The switches S_c and S_m and the current meter M are provided for determining the various currents supplied by the source. With the switch S_m in the position shown, the meter is short circuited. 20 If the switch S_m is thrown to the left, the path of the current through the meter will be from the positive terminal 212 of the power supply to the point 213, through the contact 214, to and through the successive points 215, 216, 217, 25 through the wire 218, through the contact 219 to the point 5, to the point 6, through the meter M to the point 285 to the positive line 9, through the external circuits to the negative line, so that the supervising current is read by the meter. If, 30 in addition to throwing the switch S_m to the left, the switch S_c is thrown to the left, the charging current of the battery also passes through the meter so that the meter reads the sum of the supervising and charging currents. The connections for passing the battery charging current through the meter are from the positive terminal 212 of the power supply to the point 213, through the contact 214, to and through the successive points 215, 216, 217, 5 and 6, through the meter 40 M, to the point 285 to the point 222 to the point 3, through the winding of the relay 2 through the battery to the negative line.

It will be seen that the above circuit could be greatly simplified if assurance could be made 45 that the motor relays 1 and 2 would always have exactly the same characteristics. Since, however, one of such relays is likely to operate somewhat faster than the other and thus get out of step, the foregoing construction overcomes any 50 possibility of this happening. Without such a construction the motor relays, if once out of step, would cause the rotary switches to rotate indefinitely.

The foregoing description has dealt with two 55 rotary switches. The invention, however, is capable of working with a single rotary switch of proper design and Figure 2 shows a construction in which a single motor 261 is used for the single rotary switch. In this figure, connections to the positive line are shown at 262 and 263, while connections to the negative line are shown at 264, 265, 266, 267, and 268. In the normal operation of the system, when a fire signal is given, the contact at 161 on the galvanometer relay is closed 60 and the connection is established from the positive line at 262 through the contact 269 to the point 270 through the winding of the relay 271 through the galvanometer contact 161, through the contact 272 to the negative line at 267. The 65 relay 271 is therefore energized and the contact 273 is closed. Connection is then established from the positive line at 262 through the contact 274, through the winding of the relay 261 to the point 275 through the contact 273 to the negative line 70 75

at 264. When the motor 261 is energized the breaking of the contact at 269 results in the relay 271 being deenergized so that contact 273 is opened and the motor 261 is deenergized, at which time 5 the rotary switch arm is advanced one step. The same cycle of operation is repeated until a proper balance is reached which indicates exactly the location of the fire.

In order to reset the apparatus, the push button 276 is pressed to make contact at the point 277 (the breaking of the contact at 286 causes the deenergization of the fire alarm relay M₁ with consequent return to normal conditions of the apparatus controlled thereby), so that connection 10 is established from the positive line at 263 to the point 278 to the point 277, through the winding of the relay 279 to the point 280 to the interconnected points of the rotary switch and through the movable contact 281 to the negative line at 266'. The relay 279 is energized, with the result that the contacts at 272 and 274 are broken, while contact is made at the points 282, 15 283, and 284. With the closing of the contact at 282, connection is established from the positive line at 263 to the point 278, through the contact 282, through the winding of the relay 279, to the point 280, to the interconnected points of the switch through the movable contact 281, to the negative line at 266'. Even though the push 20 button switch 276 has returned to its original position, the relay 279 remains energized until the movable contact 281 rests upon the first point of the switch. Through the closing of the contacts 283 and 284, connection is established from the positive line at 262 through the contact 269 to the point 270 through the contact 284 through the winding of the motor 261 to the point 275 through the contact 283 to the point 280 to the interconnected points of the rotary switch 25 through the movable contact 281 to the negative line at 266'. With the energization of the motor 261, the contact 269 is opened so that the motor is deenergized at which time the rotary switch arm advances one step, after which time the contact 269 is again closed, and the cycle of operation 30 is repeated until the movable contact 281 rests upon the first point of the switch.

With the connections shown in Figures 1 and 2, if it should be forgotten to restore the thermostat which has functioned, the operation of the reset push button will return the rotary switches to their initial position on the first points, but immediately the fire signal corresponding to the defective thermostat will be repeated. This 35 thermostat must be restored before the system can be returned to its normal condition.

Throughout the above description it has been pointed out that the normal position of the rotary switch or switches, is on the first contact point. The reason that the switches return to this point is that the first point is the only dead point, and through this point the motor relays can receive no energy. If a fire should occur in any of the number 1 spaces of the various circuits, the rotary switch or switches will remain on the first contact but in addition, the fire alarm lamp corresponding to the external circuit on which fire has occurred will light, the tens lamp 0 and the units lamp 1 will light, and the fire alarm bells will sound, thus indicating the existence and the location of the fire.

From the foregoing description, it will be apparent that a fire detecting system is provided embodying a minimum of wiring, the system being 70 completely supervised against wire breaks,

power supply trouble, battery trouble, external circuit alarm trouble, and external circuit fire alarm lamp trouble. A single general trouble alarm bell may be employed which may be readily cleared at all times for the indication of trouble in other circuits. The trouble alarm lamps will remain lighted until the trouble has been repaired and until the trouble alarm lamp switches have been returned to their normal 5 positions, and the system is capable of indicating exactly the location of a fire, either through manual balancing means, or automatic balancing means. The system provides for checking the results rendered either manually or automatically, and permits the checking of the restoration 10 of the thermostat that has functioned since the system cannot be returned to its normal condition unless the thermostat is restored. Variations in the resistance of the external circuits due to variations in wiring can be easily compensated for and the apparatus is capable of being arranged in a single cabinet with an appropriate door switch so that the sounding of the fire alarm bells can be stopped by the opening of the cabinet door and so that the fire must 15 be attended to and the thermostat replaced before the cabinet door can be closed again without the repetition of the fire signal. In the event that the system is not properly reset, the closing of the cabinet door can be made to operate a 20 resetting switch.

While the invention has been described with specific reference to the accompanying drawings, it is not to be limited, save as defined in the appended claims.

I claim as my invention:

1. An electro-responsive system comprising a plurality of external circuits each having two circuit wires adapted to be mounted in areas to be protected, a plurality of resistances in each 40 said circuit connected in series therein, a plurality of circuit controlling means bridged across the circuit wires of each said circuit between successive resistances of said series of resistances and adapted to be located within different areas 45 to be protected whereby each circuit controlling means serves to short circuit the resistances in the respective circuit more remote from the circuit responsive means, circuit indicating means for each circuit, area indicating means for each 50 circuit controlling means including a plurality of resistance elements corresponding to the first named resistances, a Wheatstone bridge including the last named indicating means and one of the external circuits with certain of its resistances, means operable upon actuation of a circuit controlling means in an external circuit to connect said circuit as an element of the Wheatstone bridge and to actuate the respective circuit indicating means, and means actuated by the 55 Wheatstone bridge to vary the area indicating means and to balance the second named resistances against the first named resistances included in the Wheatstone bridge for effecting a proper area indication.

2. An electro-responsive system comprising a normally closed external circuit extending through areas to be protected including a plurality of resistances connected in series therein and adapted to have a supervisory current flow 70 therethrough, a plurality of circuit controlling means adapted to be located within different areas to be protected, the resistances and circuit controlling means being connected in such fashion that each circuit controlling means 75

- 5 serves to short circuit the resistances in the respective circuit more remote from the circuit responsive means, area indicating means for each circuit controlling means and including a plurality of resistance elements corresponding to the first named resistances, a Wheatstone bridge including the indicating means and the external circuit with certain of its resistances, means operable upon actuation of a circuit controlling 5
- 10 means in the external circuit to connect the circuit as an element of the Wheatstone bridge, and means actuated by the Wheatstone bridge to vary the area indicating means and to balance the second named resistances against the first 10
- 15 named resistances included in the Wheatstone bridge for effecting a proper area indication.
3. An electro-responsive system comprising a plurality of external circuits, each including a plurality of resistances and extending through 15
- 20 areas to be protected, a plurality of circuit controlling means for each said circuit adapted to be located within different areas to be protected, the resistances and circuit controlling means being connected in such fashion that each circuit 20
- 25 controlling means serves to short circuit the resistances in the respective circuit more remote from the circuit responsive means, circuit indicating means for each circuit, area indicating means for each circuit controlling means including a plurality of resistance elements corresponding to the first 25
- 30 named resistances, a Wheatstone bridge including the last named indicating means and any one of the external circuits with certain of its resistances, means operable upon actuation of a circuit controlling means in an external circuit to connect said circuit as an element of the Wheatstone bridge, and means actuated by the Wheatstone bridge to vary the area indicating 30
- 35 means and to balance the second named resistances against the first named resistances included in the Wheatstone bridge for effecting a proper area indication.
6. An electro-responsive system comprising a plurality of normally closed external circuits, each 35
- 40 extending through areas to be protected and including a plurality of resistances connected in series therein and adapted to have a supervisory current flow therethrough, a plurality of circuit controlling means for each said circuit located 35
- 45 within different areas to be protected, the resistances and circuit controlling means being connected in such fashion that each circuit controlling means serves to short circuit the resistances in the respective circuit more remote from the circuit responsive means, circuit indicating means for each circuit, area indicating means for each circuit controlling means, a plurality of resistances corresponding to the first named resistances, connections between the last named resistances and the area indicating means, a 45
- 50 Wheatstone bridge including the first and last named resistances as the variable elements thereof, means actuatable upon actuation of a circuit controlling means in an external circuit to connect said circuit with certain of its resistances as an element of the Wheatstone bridge and to actuate the respective circuit indicating means, and means actuated by the Wheatstone bridge to vary the second named resistances to effect a 50
- 55 proper area indication.
7. An electro-responsive system comprising a plurality of normally closed external circuits, each extending through areas to be protected and including a plurality of resistances connected in 60
- 60 series therein and adapted to have a supervisory current flow therethrough, a plurality of circuit controlling means for each said circuit located within different areas to be protected, the resistances and circuit controlling means being connected in such fashion that each circuit controlling means serves to short circuit the resistances in the respective circuit more remote from the circuit responsive means, circuit indicating means for each circuit, area indicating means for each circuit controlling means in a 65
- 65 circuit, a plurality of resistances corresponding to the first named resistances, connections between the last named resistances and the area indicating means, a Wheatstone bridge including 70
- 70
5. An electro-responsive system comprising a plurality of normally closed external circuits each having an outgoing and a return wire and extending through areas to be protected, a plural- 75

the first and last named resistances as the variable elements thereof, means actuatable upon actuation of a circuit controlling means in an external circuit to connect said circuit with certain of its resistances as an element of the Wheatstone bridge, and means actuated by the Wheatstone bridge to vary the second named resistances to effect a proper area indication.

8. In combination with an electro-responsive circuit, a plurality of heat actuated devices connected in parallel in the circuit, a resistance element for each device having a partial controlling effect on an indication to be given, means to mount the devices and resistances as units, each unit comprising one device and one resistance, circuit responsive means responsive to the actuation of any one of the devices and controlling the initiation of the indication to be given, each circuit controlling means serving to short circuit all resistances in the circuit more remote from the circuit responsive means, and connections to connect the resistance of one unit with the device of the unit next most remote electrically from the circuit responsive means for control by said device, whereby destruction by fire of a resistance mounted with a device will not alter the controlling effect of said device and its controlled resistance, which latter is the resistance mounted with the device next nearest electrically to the circuit responsive means.

9. An electro-responsive system comprising an external circuit including a plurality of resistances and extending through areas to be protected, a plurality of circuit controlling means located within different areas to be protected, the resistances and circuit controlling means being connected in such fashion that each circuit controlling means serves to short circuit the resistances in the respective circuit more remote from the circuit responsive means, area indicating means for each circuit controlling means including a plurality of resistance elements corresponding to the first named resistances, a Wheatstone bridge including the indicating means and the external circuit with certain of its resistances, means operable upon actuation of a circuit controlling means in the external circuit to connect the circuit as an element of the Wheatstone bridge, means actuated by the Wheatstone bridge to vary the area indicating means and to balance the second named resistances against the first named resistances included in the Wheatstone bridge for effecting a proper area indication, and adjustable compensating resistance in the circuit to balance out variations from standard in the values of the various resistances and the resistance of the circuit.

10. An electro-responsive system comprising an external circuit including a plurality of resistances and extending through areas to be protected, a plurality of circuit controlling means located within different areas to be protected, the resistances and circuit controlling means being connected in such fashion that each circuit controlling means serves to short circuit the resistances in the respective circuit more re-

mote from the circuit responsive means, area indicating means for each circuit controlling means including a plurality of resistance elements corresponding to the first named resistances, a Wheatstone bridge including the indicating means and the external circuit with certain of its resistances, means operable upon actuation of a circuit controlling means in the external circuit to connect the circuit as an element of the Wheatstone bridge, means actuated by the Wheatstone bridge to vary the area indicating means and to balance the second named resistances against the first named resistances included in the Wheatstone bridge for effecting a proper area indication, and adjustable compensating resistances located at suitable points in the circuit to balance out variations from standard in the values of the various resistances and the resistance of the circuit.

11. An electro-responsive system comprising an external circuit including a plurality of resistances and extending through areas to be protected, a plurality of circuit controlling means located within different areas to be protected, the resistances and circuit controlling means being connected in such fashion that each circuit controlling means serves to short circuit the resistances in the respective circuit more remote from the circuit responsive means, area indicating means for each circuit controlling means including a plurality of resistance elements corresponding to the first named resistances, a Wheatstone bridge including the indicating means and the external circuit and certain of its resistances, a sensitivity changing resistance normally in series with the Wheatstone bridge, means operable upon actuation of a circuit controlling means in the external circuit to connect the circuit as an element of the Wheatstone bridge, means actuated by the Wheatstone bridge to vary the indicating means and to balance the second named resistances against the first named resistances included in the Wheatstone bridge, and means to short circuit the sensitivity changing resistance to change the voltage on the Wheatstone bridge after a predetermined actuation of the indicating means.

12. An electro-responsive system comprising a plurality of similarly actuatable resistance changing devices and resistances located at different points but connected in a single circuit through which a supervisory current is adapted normally to flow, indicating means for each resistance changing device in the circuit and including a plurality of resistance elements corresponding to the first named resistances, a Wheatstone bridge including the indicating means and the external circuit with certain of its resistances, switching means responsive to a change in value of the supervisory current due to actuation of one of the devices for connecting the circuit to the Wheatstone bridge to vary the indicating means and to balance the bridge with the second named resistances for indicating the actuated device.

HARRY CAMPBELL GRANT, JR.
